Alfred Bonom
By *William Colinton*
Attorney

UNITED STATES PATENT OFFICE.

ALFRED BONOM, OF PATERSON, NEW JERSEY.

PROPELLED BLADES FOR REVERSIBLE STEAM TURBINES.

Application filed August 12, 1921. Serial No. 491,880.

To all whom it may concern:

Be it known that I, ALFRED BONOM, a citizen of the Republic of France, residing at Paterson, New Jersey, United States of

5 America, have invented certain new and useful Improvements in Propelling Blades for Reversible Steam Turbines (for which I have filed application in France June 22, 1920, Patent No. 517,639); and I do hereby 10 declare that the following is a full, clear, and exact description of the invention, such as will enable others skilled in the art to which it appertains to make and use the same.

The present invention relates to high 15 speed fluid turbines or similar rotary engines in which inner and outer rotors are provided involving two stages, one for high pressure and the other for low pressure, and each rotor consisting of disk members, one 20 of which pertains to the high pressure stage and the other pertains to the low pressure stage, each disk being opposed by a similar disk member of the other rotor and propelling blades being arranged between the disk 25 members in each stage construction, as set forth in my former Patent No. 1,313,058 dated August 12th, 1919.

In the former patent referred to, I have 30 disclosed a means for securing the propelling blades to the disk members of each rotor and these fastening means being shown as set screws or other separable fastening members, but I have found that in building these turbines and using such fastening elements 35 for fastening the propelling blades to the disk members, that it greatly increases the cost of manufacturing the turbines and therefore the purpose of the present invention is to provide a supporting and securing 40 means for these propelling blades or structures which may be readily retained in place upon the disk members without the aid of additional fastening elements.

A further object of the present invention 45 is to provide oppositely movable sets of blades as herein set forth, consisting of a circular series of blade elements with flexible supporting means therefor carried by one of the disks, the adjacent sets of blades of one 50 rotor alternating with corresponding sets of blades carried by the opposite rotor, and with peculiar labyrinth packings between each set of blades and the inner or outer set carried by the opposite disk.

55 With the above and other objects in view, the invention consists in the arrangement

and combination of parts hereinafter described and claimed and illustrated in the accompanying drawings in which:

Figure 1 is a vertical horizontal section of 60 one of the rotors, showing a portion of a construction suitable for high or low pressure, as well as the manner in which the propelling blades are anchored within the disk;

Figure 2 is a detail section taken on the line 2—2 of Figure 1; and,

Figure 3 is a sectional view similar to Figure 1 showing a modification of the manner of mounting the propelling blades.

In my former patent above referred to, I disclose a reversible turbine having an inner and outer rotor, each of which comprises a low pressure disk and a high pressure disk which are connected to a suitable shaft. In 75 the drawings the numerals 1 and 2 indicate portions of the low pressure disks. The flow of steam is directed between these disk members in a radial direction, while the expansive force thereof is exercised against the 80 two sets of blades 3 and 4 circumferentially causing the rollers to which these blades are connected to rotate in opposite directions, either actually or relatively. The numeral 85

5 indicates a type of flexible ring connection to which one end of the blades is connected. Each of these rings 5 has the anchorage portion 6 and a relatively slender neck portion 7 therebetween. At the other side of the steam space and parallel to the ring 5 is a 90 companion floating ring 8. Blades 3 and 4 are connected up in circumferential series and are fitted between the rings 5 and 8 or formed integral therewith. The anchorage members are provided and secured to each 95 face of the disks 1 and 2 but are alternately arranged as shown and the blades 3 are alternately arranged between the blades 4 as better illustrated in Figure 2. The anchor-

age members 6 are provided with the flanged 100 portions 9 which have formed therewith and extending therefrom two or more fingers or fins 10 and the rings 8 are provided with similar laterally extending fins or flanges 11 105 which are adapted to cooperate and travel between the fins 10. These laterally projecting concentric fins 10 and 11 constitute a packing labyrinth between anchorage members fixed to the disks 1 and 2 and the floating rings 8, serving to prevent the escape of 110 steam in such a direction as would interfere with the efficiency of the machine.

Extending angularly from the inner faces of each disk 1 and 2 are the annular flanges 12 and 13. One of the anchorage members 6 has a beveled face or wall 14 which is 5 adapted to lie closely adjacent to the beveled face of the member 12. Also one of the anchorage members 6 which lies adjacent to the flange 13 has a beveled wall which also coincides with the beveled wall 15 of 10 the flange 13. In this manner it is obvious that in ascending the rotor, the anchorage members may be placed upon the respective faces of the disks 1 and 2 and when assembled will be locked between the flanges 15 12 and 13, so that when these disk members are rotated, the anchorage members and the parts carried thereby will rotate therewith. These anchorage members 6 may be welded or in any manner suitably brazed to the 20 inner faces of the disks 1 and 2, so that they will be securely fastened in place and in this manner eliminate the use of other fastening members such as screws or bolts for connecting the anchorage members and parts carried thereby to the disk members 1 and 2. The flexible neck members 7 which form a connection between the rings 5 and the anchorage members 6 not only establish a permanent connection but a thin yielding 30 connection of such a construction as to take care for the expansion of said parts due to the heating thereof by the pressure medium as well as a construction in the subsequent pull of the rotors, and also insuring the accurate centering of the several annular series of blades automatically due to their 35 high speed of rotation.

The disks 1 and 2 are thereby provided with a plurality of grooves formed between 40 pairs of flanges 12 and 13. The blocks carrying the blades 3 and 4 are placed in position within the respective grooves and before filling the last block, a lock key 13' as shown in Figure 3 is slipped in position between one block and the wall of the groove in which the block is seated so as to lock 45 these blocks in position and prevent them from moving.

Finally the last block having been placed 50 in position, forming substantially a continuous anchorage ring 16, the flanges 12 and 13 are then bent onto the corresponding inclined portion of the blocks, so as to rest upon the inclined walls thereof, thereby 55 further locking the blocks or anchorage rings into position and preventing lateral movement of the same. These flanges 12 and 13 may be bent in the various positions as 60 shown in Figure 3 according to the inclination of the adjacent surface of the anchorage member and serve not only to prevent the lateral movement of the anchorage rings, but also the radial movement of these rings, and in this manner securely lock the same 65 in position.

The spaces 20 formed between the blocks and the disks constitute air chambers adapted for interrupting, by their interpolation between said members, the communication of heat and thus serve the purpose of 70 effective insulating means.

Having thus fully described the invention, what I claim as new and desire to secure by Letters Patent is:

1. In a steam turbine the combination of 75 a pair of disks pertaining to independent rotors, said disks each having a pair of lateral flanges formed therewith and a plurality of concentrically disposed blades attached to said disks and arranged between 80 said flanges.

2. In a steam turbine the combination of 85 a pair of disks pertaining to independent rotors, said disks each having a pair of lateral flanges formed therewith, a plurality of concentrically disposed blades attached to said disks and arranged between said flanges and air chambers adapted to interrupt the communication of heat between the relatively 90 movable parts and effectively located between said parts.

3. In a steam turbine the combination of 95 a pair of oppositely coaxial disks pertaining to independent rotors, a pair of flanges diametrically disposed upon one face of each of said disks, a plurality of anchorage members arranged upon each disk and retained between said flanges and a succession of concentrically disposed blades attached to said anchorage members.

4. In a high speed steam turbine, the combination of a pair of oppositely arranged coaxial disks pertaining to independent rotors, a plurality of anchorage members brazed to one face of each of said disks, a 105 ring formed with each anchorage member, a cooperating floating ring, and blades arranged between said rings substantially as and for the purpose specified.

5. In a high speed steam turbine, the 110 combination of a pair of oppositely arranged coaxial disks pertaining to independent rotors, anchorage members secured to each disk, a ring formed with each anchorage member, a floating ring cooperating 115 with each of the first mentioned rings, blades arranged between said rings, and each floating ring cooperating with the anchorage member secured to the opposite disk substantially as and for the purpose specified.

6. In a high speed steam turbine, the combination of a pair of oppositely arranged coaxial disks pertaining to independent rotors, anchorage members secured 125 to one face of each disk, a flexible neck portion formed with each anchorage member, a ring formed with each flexible neck portion, a floating ring cooperating with each ring, a plurality of blades connecting each 130

set of rings, and a labyrinth packing between each floating ring and said anchorage members substantially as and for the purpose specified.

5 7. In a steam turbine the combination of a pair of disks pertaining to independent rotors, anchorage members secured to each disk, a ring, a flexible connection between said ring and said anchorage members, a 10 floating ring and a labyrinth packing between said floating ring and said anchorage member.

8. In a steam turbine the combination of a pair of disks pertaining to independent 15 rotors, anchorage members secured to each of said disks, each of said anchorage members having a flexible member and a flange formed therewith, a ring connected to said flexible member, a floating ring, a labyrinth 20 packing between said floating ring and said flange formed with said anchorage members, and a plurality of propelling blades arranged between said rings.

9. In a steam turbine the combination of 25 a pair of disks pertaining to independent rotors, anchorage members secured to each of said disks, each of said anchorage members having a flexible member and a flange formed therewith, a ring connected to said 30 flexible member, a floating ring, a labyrinth packing between said floating ring and said flange formed with said anchorage members, a plurality of propelling blades arranged between said rings, said anchorage 35 members being spaced from the disks to form air chambers adapted to act as insulators and interrupt the communication of heat between all relatively movable parts.

10. In a steam turbine the combination 40 of a pair of disks pertaining to independent rotors, a plurality of anchorage members secured to one face of each of said disks, flanges formed with each disk, said anchorage members being arranged between said 45 flanges, each anchorage member having a laterally extending flexible member formed therewith, a ring formed with the outer end of said flexible member, a flange formed with each anchorage member, fins extending 50 from each flange, a floating ring, fins extending from one face of said floating ring and adapted to cooperate with the fins carried by said flange, and a plurality of propelling blades connected to said rings substantially as and for the purpose specified.

55 11. In a high speed fluid turbine, the combination with two coaxial disks representing independent rotors, a succession of radially spaced blades, the blades of one disk being

arranged in alternation with those of the opposite disks, means for connecting said blades to said disks, the connecting means of each series of blades comprising a pair of coaxial rings of the same diameter, one of the rings being floating, an anchorage ring permanently connected to the other of the coaxial rings, said anchorage ring comprising a plurality of sections, means for locking said sections to said disks, and a labyrinth packing arranged between said floating ring and said anchorage rings, substantially as and for the purpose specified.

12. In a high speed fluid turbine, the combination with two coaxial disks representing independent rotors, a succession of radially spaced blades, the blades of the one disk being arranged in alternation with those of the opposite disks, means for connecting said blades to said disks, the connecting means of each series of blades comprising a pair of coaxial rings of the same diameter, one of the rings being floating, the inner faces of said disks having concentric grooves therein for the reception of said anchorage members, one of said pair of coaxial rings being flexibly connected to said anchorage members, a packing arranged between said floating ring of each pair of coaxial rings and said anchorage members substantially as and for the purpose specified.

13. In a high speed fluid turbine, the combination of two coaxial spaced disks representing independent rotors, a succession of radially spaced blades, the blades of one disk being arranged in alternation with those of the opposite disk, connecting means of each series of blades comprising a pair of coaxial rings of the same diameter, one of said rings being floating, the inner faces of each of said disks having a plurality of concentric grooves formed therein, base rings arranged within each of said grooves, each of said base rings comprising a plurality of blocks, a locking key for retaining said blocks against rotation within said grooves, flanges formed with said disks, said flanges adapted to be bent upon one wall of said anchorage rings to prevent lateral movement of the latter, one of each pair of coaxial rings being flexibly connected to each anchorage ring, and the floating ring of each coaxial pair of rings being connected by means of a labyrinth packing to the opposite anchorage ring, substantially as and for the purpose specified.

In witness whereof I have hereunto set my hand.

ALFRED BONOM.
